UNITED STATES PATENT OFFICE.

LOUIS GIAMBRONE, OF BUFFALO, NEW YORK.

COMBINED COAL AND GAS RANGE.

1,384,059.

Specification of Letters Patent. Patented July 12, 1921.

Application filed May 28, 1920. Serial No. 385,053.

To all whom it may concern:

Be it known that I, LOUIS GIAMBRONE, a citizen of the United States, residing at Buffalo, in the county of Erie and State of New York, have invented new and useful Improvements in Combined Coal and Gas Ranges, of which the following is a specification.

This invention relates to a stove and cooking range which may be heated by either solid or gaseous fuel.

One of the objects of the invention is to provide a solid fuel, coal stove which may be initially purchased at a very low cost without any gas burning fixtures, but which is nevertheless so constructed that the purchaser may at a later date make a further investment and purchase a set of separate gas fixtures which may be readily applied to the coal stove, whereby the same may be converted into an efficient gas range without in any way impairing the usefulness of the appliances which are employed in the burning of solid fuel.

A further object of the invention is to enable an unskilled purchaser of the combined coal and gas range to very easily and quickly alter the same to suit his particular requirements.

Further objects and advantages are more clearly disclosed in the following description and accompanying drawings wherein:

Figure 1 is a fragmentary front elevation of the combined coal and gas range with the gas burning appliances in position. Fig. 2 is a fragmentary vertical longitudinal section through the stove, taken on line 2-2, Fig. 3, and showing a feature of the arrangement which is used when solid fuel is being burned. Fig. 3 is a fragmentary horizontal section of the range as used when burning solid fuel, taken on line 3-3, Fig. 4. Fig. 4 is a fragmentary front elevation similar to Fig. 1, but with the gas pipes and gas manifold removed, taken on line 4-4, Fig. 3. Fig. 5 is a fragmentary horizontal section taken on line 5-5, Fig. 1, with the gas burning appliances in position. Fig. 6 is a similar fragmentary horizontal section but taken on line 6-6, Fig. 1.

Similar characters of reference indicate corresponding parts throughout the several views.

10 represents the vertical outer end wall of the stove or range and 11 the vertical outer front wall thereof. Resting upon said

vertical end and front walls is the usual top plate 12 whose edges are turned downwardly and outwardly to form the flange 13 in the manner common to the stove art, 60 said top plate containing the usual circular griddle plates or fret plates (not shown) upon which utensils containing food are placed for the purpose of heating the same.

14 represents the inner vertical front wall 65 of the stove which is arranged parallel to but in spaced relationship relatively to the aforesaid outer vertical front wall 11. At the one end of the combined range and behind the said inner vertical front wall 14 70 is the usual fire box 15 which is adapted to burn coal, wood, peat, charcoal or any other solid fuel, the same being provided with the usual pair of movable grate bars 16 and 160 and the stationary grate bars 17 for the 75 purpose of supporting the solid fuel and for removing the lower strata of ashes which accumulate at the bottom part of the fire box as the solid fuel is consumed. The one movable grate bar 16 extends forwardly 80 somewhat farther than its companion and its extreme front end is formed square at 18 in cross section to facilitate the engagement of the same with the customary shaker lever, accessibility to the same being gained 85 by a suitable shaker door 19.

Flanking the fire box on one side is the usual water box 20 which contains water that is to be heated, the same being suitably connected by water pipes to a hot water 90 storage tank in the usual and well known manner. On the other side of the fire box opposite to said water front is the customary baking or heating oven 21 which is lined with a fire brick lining 22 on the side adjacent to the fire box. It is obvious that the incandescent fuel in the fire box simultaneously raises the temperature of both the water front 20 and the baking oven 21 and also the horizontal top 12 of the range. 100

Piercing the inner vertical front wall 14 of the range are three circular apertures 23, 230 and 24, which function in a manner hereafter to be described and are shown in Figs. 2, 3 and 5, the upper two apertures being 105 horizontally in line with each other while the lower aperture 24 lies below the said upper two apertures and centrally between the same. When solid fuel is being burned in the range, these three apertures are tightly 110 sealed up simultaneously by placing in its proper position a detachable Y or triangu-

lar shaped sealing piece 25. The three ends or termini of the branches of this sealing piece are provided on their rearward sides with the annular bosses 26 which enter into 5 and engage comparatively snugly with the bores of the apertures 23, 230, and 24. Where the inner face of the wall 14 of the fire box is provided with vertical stiffening ribs 27, it is preferred that the rear face of 10 said bosses 26 be likewise provided with ribs 270, so that the vertical downward sliding movement of the solid material in the fire box is unimpeded. Formed centrally in the Y-shaped sealing piece 25 and ap- 15 proximately equidistant from the three apertures aforesaid, is a rectangular hole 28 which is adapted to receive a perforated lug 30 that is formed on and projects forwardly and outwardly from the inner vertical front 20 wall 14. By passing a cotter pin 31 or other suitable key or pin through the horizontal perforation or hole 32 of the apertured lug, the same bears against the outer face of the sealing piece 25 and holds the same rear- 25 wardly. Thus the sealing piece is held securely in place against the said oven wall and seals up all of the three apertures, all 30 sideward displacement being prevented by reason of the engagement of the annular bosses 26 with the peripheral edges of the apertures aforesaid.

It is customary practice in the construction of stoves to render the front face of the fire box accessible. This is accomplished by 35 forming a large communication opening or doorway 34 in the outer front wall 11 of the range and normally covering or closing the same by a deeply-flanged, fire box door 35 which is hung on pivots 36 and is retained 40 in its closed rearward position by the customary detent lug 37. This door is provided with three openings 38, 380 and 39 which function in a manner hereinafter to be described, and which are horizontally and 45 axially in line with their companion apertures in the inner front wall 14. It is preferred that these outer three openings be covered up in a manner somewhat different however from the means employed to cover 50 up the apertures in the inner wall 14. Extending forwardly or outwardly from the front of the door and at a point approximately equidistant from all three openings is a stud bolt 40 whose outer threaded end 55 receives a large ornamental round nut or head 41. Between the said ornamental nut and the front face of the door 35 is pivotally arranged a Y-shaped swinging cover plate 42 which swings in a vertical plane about 60 the said stud bolt 40 as a pivot. The three outer termini or the ends of the arms of the said swinging cover plate are suitably enlarged so as to be adapted to cover up or close the three aforesaid openings in the 65 door. Fig. 4 shows the swinging covering

plate in its "covering" position in full lines and its "uncovering" position in dotted lines, the two extreme positions being limited by suitable stop lugs 43 and 44, respectively. When the swinging cover plate is 70 either of its extreme positions or in any intermediate position, the same may be securely clamped to the door upon which it is mounted, by manually turning the ornamental nut 41, so that said cover plate is 75 prevented from noisily rattling when the fire box door 35 is opened or closed. The pivotal hole in the cover plate which receives the stud bolt 40 is preferably positioned sufficiently high up in the cover 80 plate, so that it is well above but perpendicularly in line with the center of gravity of said cover plate. This feature is not mechanically necessary but is commercially 85 very desirable, because the tendency of the covering plate is then always to assume its "covering" position, so that the openings in the door will always tend to cover up said openings even though the operator neglect to properly tighten the ornamental nut 41. 90 Of course, in such latter case, the cover plate will be loose and noisy but still the usefulness and the functioning of the stove will be definitely insured. It will be now more clearly understood that the stove is adapted 95 to burn solid fuel when both said Y-shaped swinging cover plate 42 is in its "covering" position and likewise the Y-shaped sealing piece 25, as shown in Figs. 2, 3 and 4.

When however it is desired to convert this 100 solid fuel stove or range into a gas burning range, certain alterations are provided for. The owner of the stove who desires to use gas as a fuel, makes the following purchases 105 either at the time he originally purchases the coal stove, or at any time subsequent thereto: a T-shaped gas manifold 46, a pair of manifold brackets 47, two gas pipes 48 and 480 with burners; and a combined oven-heating and water-front gas pipe 50. When 110 the purchaser obtains these items, he first attaches the two manifold brackets 47 to the stove by means of stove bolts 51, the latter passing through suitable holes which have previously been drilled in the down-turned flange 13 of the stove top 12. Then 115 he mounts the T-shaped manifold 46, with its three gas valves, on said brackets 47 and tubularly connects said manifold to the gas supply mains by suitable piping 52, elbows 53, etc., in the usual manner. Then he loosens the ornamental nut 41 and turns the 120 swinging cover plate 42 to the dotted line position of Fig. 4 and preferably again tightens the said ornamental nut to prevent rattling. He then opens the door 35 and removes the cotter pin 31 and the Y-shaped sealing piece 25 and passes the three gas pipes 50, 48 and 480 successively from the fire box out through the front of the stove 130

and into engagement with their companion gas valves. The stove is now suited to burn gaseous fuel, and the same may obviously be converted back to a coal stove whenever 5 desired. It is obvious also that the original purchaser may purchase the stove as a gas range *per se* if he desires without the grate bars, ash pan and other coal burning appliances, so that his initial investment for 10 the gas stove is just that much less. Then later when circumstances are altered, he can remove the gas apparatus and purchase and install the grate bars etc., these being easily placed in position in a manner common to 15 the stove art.

Each of the three gas pipes is mechanically supported at its outer or forward end in the companion opening in the door 35, while its central part is supported on suitable shoulders formed just below the companion aperture in the inner wall 14. The upper two burners 48 and 480 are supplied at their rear ends with the usual star-shaped burners 55 and 550 but the lower gas pipe 20 50 is of novel construction, as shown in Fig. 6. This lower gas pipe is supplied with an annular supporting collar 56 which rests on a suitable shelf on the inner side of the inner wall 14, and is thus capable of rotation about its central axis. Extending out 25 laterally and then projecting longitudinally backwardly from the gas pipe proper is a branch pipe 57 whose outer side is pierced with a longitudinal row of gas holes 58. In 30 the full line position of Fig. 6, these holes direct the flaming gas against the fire brick 22 of the backing oven 21, thereby heating said oven. When, however, it is desired to heat the water front 20, the branch pipe 57 35 is swung over to the dotted line position of Fig. 6, in which case the gas flames are directed against the adjacent wall of said water front and thereby raise the temperature of the water therein. If desired, two 40 branch pipes may be supplied, one for just the water front and one for just the heating oven, which is doubtless more convenient but materially more expensive, inasmuch as double the amount of piping and an additional 45 gas valve on the gas manifold would 50

be required. Therefore for commercial reasons the construction shown of the combined water front and oven heating pipe is preferred, this gas pipe being less frequently used than either of the two griddle heating 55 gas pipes 48 and 480. A stove having the characteristics of this improved combined coal and gas range should not be confused with the stoves now on the market which are adapted to burn either solid or gaseous 60 fuel without any radical mechanical alterations. Such stoves have an undoubted market but they do not meet the full requirements, that is, they are very costly because purchaser is buying the complete gas- 65 coal stove. In this invention the purchaser may buy either a stove for gas or a stove for coal and alter the same to burn a different fuel at any time in the future he desires, and he may at that time make additional 70 expenditures for the additional equipment.

I claim as my invention:

1. A combined coal and gas range having an opening in one of its vertical walls, a combined water front and oven heating gas 75 pipe adapted to pass through and to be rotated in said opening and having a laterally-extending branch pipe, and means for covering up said opening when said combined gas pipe is not being used. 80
2. A combined coal and gas range comprising a fire box, an oven arranged on one side of said fire box and a water front arranged on the other side of said fire box, a combined water front and oven heating gas 85 pipe capable of rotation about its central axis and provided with a laterally and longitudinally extending branch pipe which is adapted to be swung either against said water front or against said oven. 90
3. A combined coal and gas range provided on one of its vertical walls with several openings arranged in the shape of a triangle, a T-shaped gas manifold detachably connected to said range with its arms 95 arranged in front of said openings, and several gas pipes adapted to be passed through said openings and to be detachably connected to the arms of said gas manifold.

LOUIS GIAMBONE.
